CLAIM

The ornamental design for an implant, as shown and described.

DESCRIPTION

The patent or application file contains at least one drawing executed in color. Copies of this patent or patent publication with color drawing(s) will be provided by the Office upon request and payment of the necessary fee.

FIG. 1 is a front elevation view showing our new design; FIG. 2 is a rear elevational elevation view of FIG. 1; FIG. 3 is an enlarged detail view of a portion of FIG. 1; FIG. 4 is a left side elevation view of FIG. 3; FIG. 5 is a right side elevation view of FIG. 3; FIG. 6 is a top plan view of FIG. 3; and, FIG. 7 is a bottom plan view of FIG. 3.

The broken lines of FIGS. 1-2 and 4-7 show portions of the implant that form no part of the claimed design. FIGS. 1, 3, and 5-7 include portions shown in the color purple, and the stippled regions represent a color contrasting with the purple color. The dash-dot broken lines of FIGS. 4-7 represent boundaries of the claimed design and form no part of the claimed design.

1 Claim, 4 Drawing Sheets
(3 of 4 Drawing Sheet(s) Filed in Color)
